UNITED STATES PATENT OFFICE

2,506,895

ANTIMICROPHONIC "V" TENSION ROD

Paul H. Sassaman and Donald R. Kerstetter, Emporium, Pa., assignors to Sylvania Electric Products Inc., a corporation of Massachusetts

Application December 24, 1948, Serial No. 67,154

7 Claims. (Cl. 250—27.5)

1

The present invention relates to electron discharge devices and more particularly to a means for mounting vibration free filamentary cathodes in such devices. The usual electrodes assembly of electron discharge devices includes more or less concentric anode grid and cathode electrodes supported in position between parallel insulating spacers. In the case of filamentary electron discharge devices, the filamentary cathode ordinarily passes through holes in the spacers at or near the axis of the tube, and means are provided for applying a tension to the filament so that it lies in a substantially straight line between the two spacers and under some degree of tension. One end of the filament is ordinarily directly secured to a lead-in conductor, while the other end is connected to a spring tension support and thus to another lead-in conductor which may pass through the spacers near their edge. It is desirable to provide a tension on the filament which may readily be adjusted to a constant value as between successive tubes, so that the relationship of the filament to the other electrodes of the discharge device is maintained constant. If the tension is insufficient nonuniformity in operation of the discharge devices may result due to improper spacing and sagging of the filamentary cathode. Jars and vibration of the discharge devices tend to produce vibration of the cathode, with consequent interference with normal operation. Furthermore, vibration of the filamentary cathode tends to cause a sliding motion of the filament wire against the edge of the aperture in the spacer members, thus either sawing the hole larger which allows displacement of the filamentary cathode, or weakening the cathode so that it is readily fractured. It has been discovered that lateral vibration of the spring tension device is particularly liable to wire breakage of the filament. Thus, it is particularly important to prevent any lateral vibration of the filament and especially of the filament tensioning means. Still, the tensioning means should not be so complicated in construction so as to make assembly difficult or such as to unduly increase the cost of manufacture of the tube. Also, the tensioning device must be capable of absorbing any reasonable elongation of the filament without lessening the amount of tension to any marked degree. Finally, the tensioning device must be capable of being easily adjusted to give maximum tensions.

An object of the present invention is the provision of a suspension for filamentary cathodes

2

whereby said cathodes are maintained in fixed position.

Another object of the present invention is the provision of a resilient suspension for filamentary cathodes which inherently is resistant to lateral vibration.

Another object of the present invention is the provision of a tensioning arrangement for filamentary cathodes which results in a much lower microphonic level for the tube in which it is placed than presently known constructions.

A further object of the present invention is the provision of an inexpensive, readily constructed filament tension arrangement for electron discharge tubes.

Still a further object of the present invention is the provision of a filament tensioning arrangement which may readily be used in any type of filamentary cathode discharge tube, regardless of grid spacing or grid side rod size.

Still another object of the present invention is the reduction of manufacturing shrinkage in the manufacture of filamentary electron discharge devices.

25 Still a further object of the present invention is the provision of a filament tensioning construction which may readily be adjusted by factory operators and which will not involve additional difficulty in mounting the device.

30 The foregoing objects and results are attained in accordance with an aspect of the present invention by providing a top filament tensioning arrangement in the form of a generally U or V shaped tension rod of comparatively small trans-

35 verse dimensions, having the top filament tab connected to the tension wire at somewhere near its mid-point. The ends of the tension wire are welded or otherwise secured to tabs on a transverse fixed support over the top spacer mica.

40 By varying the amount of bend in the tabs the amount of tension applied to the filament may very accurately be adjusted. Also by limiting the diameter of the tension rod to a certain range of sizes which has been found to work well, the

45 maximum operating range of the tension arrangement may be increased such that a reasonable elongation of the filament does not lessen the amount of tension to a marked degree.

The present invention will be more fully understood by reference to the following detailed description which is accompanied by a drawing in which

Fig. 1 shows, in an elevational view, an electron discharge device embodying the principles 55 of the present invention, while

Fig. 2 is a perspective view of a filament tension hook according to principles of the present invention.

In Fig. 1 there is shown an electron discharge device generally indicated by reference character 10. The device may include within an evacuated casing 12 a mount assembly 14. The particular tube shown here includes in mount 14 a filamentary cathode 16, and surrounding the cathode a grid 18 and an anode 20. Grid 18 and anode 20 are maintained in position by insulating spacers 22 and 24. While not so shown in this figure, it is customary to provide apertures in the spacers 22 and 24 through which extensions of the side rods of grid 18 and tabs on anode 20 pass, whereby the assembly is maintained in its operative arrangement. The filamentary cathode passes through small holes at about the axis of the tube. One of the holes is indicated by reference character 26 and is preferably triangular in form as shown in Fig. 2 with one apex at the axis of the mount. The lower end of the filamentary cathode 16 is secured through tab 28 to a support 30 attached to a lead-through electrode 31 which extends through the glass header of the tube and forms a connection pin on the exterior of the discharge device. The other end of the filament is connected through tab 32 to a tension spring arrangement generally indicated by reference character 34 which is supported on the upper end of support rod 36. The lower end of support rod 36 is connected to another lead-through electrode 38 which passes through the header of the tube to form a second plug-in connection pin for the tube. The grid and anode of the triode structure are also connected to other lead-through electrodes which are not specifically identified as they are not concerned with the present invention.

While our invention is not limited thereto, we have chosen to illustrate in Fig. 1 the application of our invention to a tube having a lock-in type of plug-in base wherein the lead-through conductors 31 and 38 actually form connection pins at the bottom end of the tube. Also, the tube shown in Fig. 1 is a dual purpose type of tube having a second electron discharge arrangement beneath spacer 24, but since this arrangement is not part of the present invention it will not be further described here.

In Fig. 2 we have shown in greatly enlarged perspective view the filament tensioning arrangement shown in elevation in Fig. 1. From this figure it will be seen that support rod 36 passing through the upper spacer 22 has secured thereto a short L-shaped member 40, carrying a transverse member 42 having along its upper edge a pair of tabs or lugs 44 and 46. Lying across the upper surface of bent-over connection tabs 44 and 46 are the two ends of tension rod 34. The rod is preferably bent into a generally U or V shaped formation. Near the free ends of rod 34 they are secured to the tabs 44 and 46, for example, by spot welding. Filament 16 has secured to its upper end a folded over connection tab 32. Tab 32 is welded to tension wire 34 at substantially its mid-point, that is, it is welded to wire 34 at substantially the apex of the V. By means of a series of tests we have discovered that the best results from the present arrangement are obtained if the tension wire 34 has a diameter of between four and one-half and five thousandths of an inch, and if its width, that is the distance between tabs 44 and 46, is fairly large

compared to the distance between member 42 and tab 32, thus forming a short V. With a short substantially equilateral V, we have discovered that the point of attachment of tab 32 to tension wire 34 is not particularly critical. It need not be exactly at the apex, nor need tension wire 34 be formed into a sharp pointed V, but a bowed formation is all that is necessary. Nor is it necessary for wire 16 to fall directly into one of the corners of the triangular hole 26. Its position is maintained very well even though it is originally placed so that it lies somewhere along the middle of one of the sides of the triangle.

Tests indicate that a top tension arrangement as shown in Fig. 2 produces a tube with a lower microphonic level than could be obtained with other tensioning arrangements of which we are aware, plus the use of grid dampeners, that is insulated members secured to the grid support rod, and bearing against the filament somewhere between the spacer plates 22 and 24. By using tension rods having diameters of the order specified above, it has been found that it is possible to get a larger and more uniform tension on the filament wire 16 than would be possible with a heavier tension rod, because there is much less possibility of putting a permanent set in the wire 34, when the preferred relationship of diameter and length is used. It is believed also that the excellent performance of the present invention with regard to microphonic tendencies of the tube may be predicated on the fact that the top of the filament is supported from vibrating in a lateral direction by the two arms of the tension rod forming a comparatively obtuse angle with one another. Also, since tension rod 34 is comparatively light, microphonism can not be initiated or sustained by reason of the vibration of the top tab and the weight of the resilient mounting means. The tension applied by tension spring or rod 34 may be adjusted accurately over a substantial range of values by bending lugs 44 and 46 downward toward plate 42. Also, it should be noted that since the welds between tabs 44 and 46 and wire 34 is made near the extreme ends of wire 34, any weakening of the wire 34 caused by the welds does not extend to the region of the wire where the maximum bending takes place.

While we have shown and particularly described an embodiment of the present invention, it should be clearly understood that it is not limited thereto, but that modifications within the scope thereof may be made.

What we claim is:

1. In an electric discharge device having a filament with connector tabs at its ends, means for supporting said filament including a fixed support adjacent one end of said filament, a support carrying a transverse member having a number of bent over lug portions directed away from said filament, and a spring member having a bend intermediate its ends, and its ends secured to said lugs, and means for securing one of said connector tabs to said spring intermediate its ends, said spring member lying across the bends in said lugs.

2. In an electric discharge device having a filament with connector tabs at its ends, a support carrying a transverse member having a number of bent over lug portions directed away from said filament, and a spring member having a bend intermediate its ends, and its ends secured to the ends of said lugs, and means for securing one of said connector tabs to said spring intermediate

its ends, said spring member crossing the bends in said lugs.

3. A tension device for use in electron discharge devices including a resilient rod-like member having a bend intermediate its ends, a transverse member having bent-over lugs to which the ends of said rod-like members are attached, said rod lying across the bends in said lugs.

4. A tension device for use in electron discharge devices including a resilient rod-like member having a bend intermediate its ends, a transverse member having bent-over lugs to which the ends of said rod-like members are attached, said rod lying across the bends in said lugs, the length of each of the legs of said rod being substantially equal to the length of said transverse member.

5. A tension device for use in electron discharge devices including a resilient rod-like member having a bend intermediate its ends, means for securing an end of a filament to said bend, a transverse member having bent-over lugs to which the ends of said rod-like member are attached said lugs being directed away from said filament.

6. A tension device for use in electron discharge devices including a resilient rod-like member having a bend intermediate its ends, means for securing an end of a filament to said bend, a transverse member having bent-over lugs to

15

25

which the ends of said rod-like member are attached, said rod lying across the bends in said lugs said lugs being directed away from the bend in said rod-like member.

5. A tension device for use in electron discharge devices including a resilient rod-like member having a bend intermediate its ends, means for securing an end of a filament to said bend, a transverse member having bent-over lugs to which the ends of said rod-like member are attached, said rod lying across the bends in said lugs, the length of each of the legs of said rod being substantially equal to the length of said transverse member.
